(57) **CLAIM**

The ornamental design for a plate dispenser, as shown and described.

DESCRIPTION

FIG. 1 is a top, front, left side perspective view of a plate dispenser showing my new design;

FIG. 2 is a top, front, left side perspective view thereof;

FIG. 3 is a top, front, left side perspective view thereof, shown in an alternate, slightly expanded position;

FIG. 4 is a front elevation view of the position shown in FIG. 2;

FIG. 5 is a rear elevation view thereof;

FIG. 6 is a right side elevation view thereof;

FIG. 7 is a top plan view thereof;

FIG. 8 is a top plan view of the expanded position shown in FIG. 3; and,

FIG. 9 is a bottom plan view of the position shown in FIG. 2. Portions shown in broken line are for illustrative purposes only and form no part of the claimed design.
